Elmer H. Daniels, Pasadena, Calif., assignor to
The Plomb Tool Company, Los Angeles, Calif.,
a corporation of California

Application February 25, 1946, Serial No. 127,270

Term of patent 14 years

(Cl. D93—4)

To all whom it may concern:

Be it known that I, Elmer H. Daniels, a citizen of the United States of America, residing in the city of Pasadena, in the county of Los Angeles, State of California, have invented a new, original, and ornamental Design for a Hammer Head, of which the following is a specification, reference being had to the accompanying drawings, forming a part thereof.

Fig. 1 is a side elevational view of a hammer head showing my new design;

Fig. 2 is a side elevational view thereof taken at right angles to Fig. 1; and

Fig. 3 is a top plan view thereof.

I claim:

The ornamental design for a hammer head, substantially as shown.

ELMER H. DANIELS.
